Edward J. Garey, Attorney.

UNITED STATES PATENT OFFICE.

ALFRED BARCLAY FRACK, OF GIRARD, OHIO, ASSIGNOR TO HENRY C. MARSHALL, OF SAME PLACE.

WRENCH.

SPECIFICATION forming part of Letters Patent No. 601,851, dated April 5, 1898.

Application filed July 26, 1897. Serial No. 645,876. (No model.)

To all whom it may concern:

Be it known that I, ALFRED BARCLAY FRACK, a citizen of the United States, residing at Girard, in the county of Trumbull and State of Ohio, have invented certain new and useful Improvements in Wrenches, of which the following is a specification, reference being had therein to the accompanying drawings.

My invention relates to wrenches and is more particularly of that class commonly known as "monkey-wrenches;" and it combines certain mechanical parts and instrumentalities to be fully and clearly described with the aid of the accompanying drawings, in which—

Figure 1 represents a side elevation of the invention. Fig. 2 is an end view thereof. Fig. 3 is a longitudinal sectional view of Fig. 1. Fig. 4 is a cross-sectional view upon the line $\alpha\alpha$, and Fig. 5 is a cross-sectional view upon the line yy of Fig. 1.

In the several views the same letter always indicates the same part of the invention.

J represents the head-jaw of a wrench constructed after the manner of my invention, having a stem comprising a part J^2 of a rectangular transverse section and an extended part J^3 of a circular transverse section, in the cylindrical surface of which last is recessed the blind spiral groove T, of semicircular contour.

The twin jaw J' of the wrench is provided with a strap Z, embracing the portion J^2 , and a parallel strap Y, engaging the portion J^3 of the stem, the said strap Y continuing into the lug X, with concaved face W, into which rests the round portion V of the hollow handle H, mounted upon the stem J^3 and ending in the annular flange U, engaging the circular recess R of the lug X, and thereby maintained in its position upon the stem.

The annular flange U is provided with a series of blind slots or recesses s, into which may be engaged the sliding key L, dovetailed into the longitudinal slot s' of the lug X.

In the body of the handle H is an opening O, screw-threaded and engaging the set-screw S, having a rounded recess in its inner end adapted to contain the ball B, racing in the before-mentioned groove T.

From the description of the mechanical parts of my invention the operation thereof will be readily understood to be as follows—that is, the handle H being rotated upon the stem J^3 and being firmly held in juxtaposition to the jaw J' by the engagement of the flange U with its seat R the stem J^3 will be thrust outward by means of the impact of the ball B upon the groove T, thereby separating the jaw J from the jaw J' . The reverse movement will again close the jaws. The said jaws may be maintained in any determined position by thrusting the key L into engagement with one of the slots s, the slot s' being sufficiently large to permit the longitudinal play of the said key, and the same may be released by a sliding movement of the thumb upon the said key.

Having fully described my invention and its operation, what I desire to secure by Letters Patent and claim is—

In combination with a jaw, the integral stem thereof with a blind helical groove about the said stem, a jaw slidably mounted upon the said stem and having an extended lug with the key and slot therefor and the circular recess, the hollow handle slidably mounted upon the stem, the annular flange of the said handle engaging the said circular recess, the set-screw threaded into the said handle, the hollow end of the said set-screw, and the ball playing in the said hollow and in the before-mentioned blind helical groove, all substantially as described.

In testimony whereof I affix my signature in presence of two witnesses.

ALFRED BARCLAY FRACK.

Witnesses:

I. C. PROCTOR,
E. C. WEAVER.
